United States Patent Office

Des. 193,980
Patented Nov. 6, 1962

193,980

CHAIR OR THE LIKE

Herbert Ritts, P.O. Box 64336, Los Angeles 64, Calif.

Filed Aug. 18, 1961, Ser. No. 66,406

Term of patent 7 years

(Cl. D15—1)

Fig. 1

Fig. 2

Fig. 3

Fig. 4

FIGURE 3 is a side elevational view of the chair, taken from the side opposite to that shown in FIGURE 1; and FIGURE 4 is a top plan view of the chair.

I claim:

The ornamental design for a chair or the like, substantially as shown.
